FOOT CASTS AND PROCESS OF MAKING
THE SAME

Alan E. Murray, New York, N.Y.

Original application October 27, 1954, Serial No. 465,109.
Divided and this application May 6, 1955, Serial No.
506,435

18 Claims. (Cl. 18—55.05)

My invention relates particularly to foot casts and the method of producing them, wherein greater accuracy and control in making the same is attained.

This application is a division of my copending application upon Interdigital Toe-positioners, Casts, Footwear, Process of Making the Same and Products Thereof, Ser. No. 465,109, filed October 27, 1954.

An object of my invention is to make possible the production of casts which more accurately and faithfully conform to the actual foot shape of the wearer of shoes made therefrom.

A further object is to provide foot casts which retain the true position of the toes and metatarsal region of the foot as a result thereof.

Another object is to eliminate the previous residual difficulties encountered at times in securing an actual reproduction of the true shape of the feet.

Further objects of my invention will appear from the detailed description of the same hereinafter.

While my invention is capable of embodiment in many different forms, for the purpose of illustration I have shown only certain forms thereof in the accompanying drawings, in which:

Fig. 1 is a plan view of one form of a toe-positioner or toe-lock;

Fig. 2 is a similar plan view of a smaller-sized toe-positioner or toe-lock;

Fig. 3 is a plan view of a foot showing the position of said toe-lock thereon;

Fig. 4 is a vertical transverse section of the same taken on line 4—4 of Fig. 3;

Fig. 5 is a vertical longitudinal section of a bread pan containing a spherical supporting plate with a rectangular outline;

Fig. 6 is a vertical transverse section of said spherical supporting plate taken on line 6—6 of Fig. 5;

Fig. 7 is a plan view of a felt sheet partly broken away, carried on said plate;

Fig. 8 is a side elevation of said bread pan having instead therein plaster of Paris covered by burlap;

Fig. 9 is a plan view of the pan, plaster and burlap of Fig. 8;

Fig. 10 is a rear elevation of one of the inserts having top and bottom members, for the top and bottom of the foot;

Fig. 11 is a plan view of the insert of Fig. 10;

Fig. 12 is a plan view of each of the two pieces of jersey cloth for forming said insert;

Fig. 13 is a plan view of a toe-positioner sock used in place of the jersey cloth shown in Fig. 12;

Fig. 14 is a plan view of the insert shown in Fig. 10, showing ventilating holes therein; and

Fig. 15 is an elevation partly in section of a cast made with surgical wrappings.

In carrying out my invention, I preferably make a toe-positioner or insert such as the toe-lock shown in Fig. 1 or 2. Referring to Figs. 1 to 4, in making the said toe-positioner as an interdigital toe lock, I may make a full

2

sized insert 1 for the top of the foot, as shown in Fig. 1, or I may make a smaller insert 2, shown in Fig. 2, which are made the same except for the fact that in the insert 2 a greater portion is trimmed from around the same, as hereinafter described. Also, the procedure in making said inserts 1 and 2 is substantially the same for the left foot 3 and the right foot, respectively. For this purpose, the foot 3 is placed on any desired surface, which may be a flat surface of a table top, while the wearer may be seated on a chair located on the table and with the weight of the foreleg resting on the table top. Preferably instead, however, I may rest the foot 3 on any chosen portion of a ball-shaped surface 4, as shown in Fig. 4, in accordance with the procedure of supporting the feet as described in my copending application upon Method of Making Footwear and Products Thereof, Ser. No. 385,094, filed October 9, 1953, now Patent No. 2,742,717, in order to provide convex supporting surfaces at either side of the top of the ball surface for the respective left and right feet, the said portions of which surfaces approximately conform to the underneath concave curvatures of the arches or metatarsal regions of the respective feet.

Thereupon, I place over the front portion of the foot, as shown in Fig. 3, a piece of jersey cloth 5, which is the material from which underwear is made, that is to say which is very stretchable into any desired 3-dimensional shape. The cloth 5 is preferably woven on a tubular, or convex, form so that the threads in the weaving take a circular or curved direction when being woven.

Thereupon, I prepare a mud made of thickened neoprene latex or any other latex, which may be thickened as set forth in my application Ser. No. 385,094 aforesaid, or in my Patent No. 2,568,291 referred to therein. Of course, any rubber, or artificial rubber, latex of a similar character could be used instead, to make the mud. Into an amount of the said thickened neoprene latex sufficient to form a positive cast, I knead a quantity of diced felt, such as $\frac{1}{8}$ " cubes, or granules of a smaller size, to produce a consistency about like that of cottage cheese. The said felt is preferably of the cheap gray flooring felt, which is generally made from mill ends or waste and which is comprised generally of 40% wool and 60% cotton waste comprising the various impurities commonly present in such waste. However, instead of the said felt, other types of felt could be used, or wool flocks or cotton flocks or rayon flocks, etc. Also, therewith, I may or may not introduce into the thickened latex and felt granules any desired quantity of a filler, such as wood flour. This, for example, may be a pine wood flour or any other one or more kinds of wood flour. This mud, with or without the filler, may have the proportions of the three different materials widely varied to produce the desired consistency, but, for example, it may be comprised of one part by volume of the thickened latex, one part by volume of the diced felt, and one-half part by volume of wood flour.

The jersey cloth 5 is now pressed down between the toes to the surface 4, with the aid of a dull tool or table knife, into the recess between the big toe and the next toe, and while so pressed down a quantity of the mud 6 is forced, with the fingers, into the cloth within the recesses from above. The other three toe recesses are then filled in, in a similar way, one after another, until the cloth 5 and the mud 6 is extruded beneath and towards the adjacent underneath portions of the respective toes, as shown in Fig. 4. This results in the production of two wrinkles 7 and 8 at the rear of each of the toe recesses, which are thereupon snipped off with a pair of scissors. Some of the thickened latex is then applied on top of the cloth 5 extending outwardly to a marginal link 9, as shown in Fig. 3, which extends considerably

beyond the outer margins of the front of the foot, so that this entire portion of the cloth 5 becomes completely saturated with the latex. Thereupon, I shake some powdered plaster of Paris all over the top of the impregnated cloth 5. Then, I apply a second, or top, piece of jersey cloth 10 of the same size and character as that above referred to, which is placed over the top of the cloth 5 and the interdigital mud toe-separators 6, and mold the same downwardly with the fingers, all over the top at the front metatarsal portion of the foot and toes. The latex, meantime, will have completely saturated the top cloth 10. Then, with a table knife, I mold the jersey cloth pieces 5 and 10 underneath the toe ends and over and beyond the opposite edges of the foot, as shown in Fig. 4. Next, I brush over the top of the said cloth 10 some thickened latex so that the cloth becomes well impregnated therewith. A fan, or hair dryer producing a current of heated air, is then directed onto the said foot support for about fifteen minutes, whereupon the latex and powdered plaster of Paris will have become partly set, and sufficiently dried for the insert to hold its shape.

The foot is now carefully removed from the insert. This can be readily done because of its elasticity, and in spite of the extruded enlarged lower portions located between the toes, as shown in Fig. 4. The fan, or hair dryer, is now directed onto the support for about twelve hours, in which time the same will have become substantially completely set and capable of being worn on the foot. Alternatively, if it is desired to further conform the insert to the foot in any given instance, it can be replaced and worn on the foot within less than the said twelve hours to completely shape it and intimately conform it to the interdigital recesses and in complete conformation with the other foot contours.

The insert thus made, before being returned to the foot for general or permanent wear, may be cut off around the line of the marginal indentation 11, as shown in Fig. 4, on both sides of the foot and in front of the toes so as to produce the full size support 1, as shown in Fig. 1. However, if a smaller insert is desired, instead, it may be cut along a line 12, as shown in Fig. 3, or at any other desired outline thereon. Also, if desired, the extruded portion 6 between the toes, as shown in Fig. 4, may be cut off somewhat along a line or level 13, as shown in Fig. 4, or to any other desired degree, while still leaving downward portions thereof extruded between the toes laterally in the interdigital spaces.

As an alternative procedure, the final insert may be made of sponge rubber, especially as sponge rubber is more elastic and compressible than the materials of which the inserts 1 and 2 have been made. For this purpose, I may make initially an insert as above described, after which any desired negative plaster of Paris cast may be made of said insert. Then I finally pour into the said plaster negative a moldable rubber or a sponge rubber material or composition which, when solidified carries therein throughout the body of the rubber small cavities, having the usual compressibility of sponge rubber.

As a further modification of the latter alternative method, instead of making the initial foot support of the two pieces of jersey cloth 5 and 10 and the mud 6, I may make the initial model by means of a moulage or by forming a plastic mold of "Plastelene," which is a non-setting mixture of clay and a mineral oil, or of the dental molding material commonly used by dentists, doctors, artists, etc., for making molds of the different portions of the human body. When the initial mold is made as a positive plaster cast, then a negative can be made therefrom, after which the sponge rubber insert can be molded therein, as above described.

The insert thus made by any of the above procedures will provide an effective support for the foot by, in effect, suspending the toes from the upper surface of the foot, and can be worn on the foot inside the shoe, with or

without a sock, even when the shoe is non-fitting or oversized, while preserving the position of the toes and the shape of the foot, or it may be worn within a sock without a shoe, especially as the support will effectively resist the usual tendency of the sock or shoe or both to produce undesirable displacements of the toes. Also, the inserts 1 and 2, while locking the toes in their true relation, will, nevertheless, permit bending and free movement of the toes during the exercise thereof.

10 The said toe-lock 1 or 2, but preferably the smaller toe-lock 2, may now be used for making a more accurate cast of the foot on which a shoe is to be made. For this purpose, the toe-lock 2 may be placed on the foot so as to hold the toes in position accurately, and the foot 15 with the toe-lock thereon may then be used to produce a very accurate negative cast, followed by the making of an accurate positive cast therefrom, in accordance with the procedure described, for example, in my Patent No. 2,177,734, granted December 24, 1939. When the positive plastic cast is obtained therefrom the toe-lock 2 may be placed on the cast and a molded shoe built therefrom in accordance with any of the procedures in my previous patents. In wearing the shoe the wearer will, preferably, wear the said toe-lock 2 on the foot beneath a sock within the shoe.

20 Or, as an alternative method of making a cast, I can proceed as follows: In making a negative cast in the following way, I am enabled to tighten up the tissues of the foot without losing the relative shape of the different parts of the foot. This procedure draws the foot together while keeping its approximate shape, due to the presence of a toe-positioner or toe-lock. For this purpose, the foot may be supported upon an appropriate portion of the curvature 4 of the ball or spherical surface, such as is described in my copending application Serial No. 385,094 aforesaid, having a radius of approximately 36". For convenience, I may provide, as shown in Figs. 5 and 6, a spherical surface 14 selected from the surface of said sphere 4 which conforms most closely to the curvature of the under side of the particular foot, and the said surface may be embodied in a rectangular metal plate 15 having a cavity 16 beneath the same for lightness. The said surface 14 is, for instance, chosen for the left foot of the wearer having the toe position 30 near the left end of Fig. 5 and the heel position towards the right end thereof. This rectangular plate 15 is preferably made so as to fit within the bottom of a rectangular bread pan 17 having upwardly flaring sides. A rectangular piece of felt 18, as shown in Fig. 7, is now provided, made from approximately $\frac{1}{4}$ " thick felt, such for instance as the felt above referred to, or other fibrous materials. The felt piece 18 having now been placed on the surface 14, a layer of sand 19, about $\frac{1}{8}$ " thick, is scattered on top of the felt 18. Thereupon, the procedure of making the negative cast, followed by the making of a positive cast, may be carried out in accordance with the procedure in my patent aforesaid, No. 2,177,304. However, instead, in making a negative cast while the foot is rested on the said 19 supported by the felt 18, a little sand is preferably placed between the toes to prevent the toes from becoming locked to the plaster. With a spoon, I now apply the plaster of Paris and water mixture having a consistency of heavy cream, around the foot down to where the foot meets the sand 19 and so as to extend slightly beneath the undercut line and extending up to above the ankle joint. Weakening vertical marks are now made thereon by scoring both sides of the plaster of Paris on opposite sides of the foot opposite to the ankle joint so that this part of the cast can be separated into two pieces later. When this plaster is hard, the foot is raised together with the upper portion of the negative cast or baffle thereon. A second pan of the same kind as the pan 17 is now prepared, filled with the said plaster of Paris cream to a level somewhat higher than the level of the sand 19 in the first pan 17,

and the foot, having thereon the upper negative cast, is transferred to said second pan while the operator presses this negative upper cast and the foot down into the second pan. During this operation, the foot will retain its ball-like underneath curvature and will transfer the shape thereof to the plaster lower half of the negative in the second pan. This negative, when removed in three separate portions from the foot, is then reunited and used for making a plaster of Paris positive therein and then a shoe may be built on this positive.

However, it is one of the purposes of my invention to produce a cast which may be constructed either for a soft foot or a hard foot, as desired. A cast and shoe like those just described may be suitable for wear by a hard foot. However, in making a cast especially adapted for a soft foot, I may produce the cast in such a way as to exert a pressure equally throughout on the foot by applying pressure to the exterior of the plaster while it is setting, which may be produced by making a negative plaster cast with the toe-lock 2 or 1, if desired. Accordingly, I provide a bread pan of the same type as the pan 17, and I prepare a large basin, about 12" in diameter, containing some of the said plaster of Paris cream, but which is preferably salted by the addition thereto of about a half a tablespoon full of ordinary salt. Then I pour about one third of this salted plaster of Paris cream into the bread pan. The foot with the toe-lock on it, preferably, powdered with talcum powder, is then lowered into the plaster of Paris in the bread pan to approximately the undercut line of the foot. Now, the plaster of Paris is leveled off at the undercut line with the fingers or back of the spoon. The procedure followed in this example of my invention enables the entire negative casting of the foot to be accomplished simultaneously. Accordingly, the leveled off plaster of Paris, as above referred to, is then covered over with about eight or more small pieces of newspaper 20, until the entire surface of the plaster of Paris is covered thereby, although the pieces of paper need not accurately fit around the foot. Then I spoon in, over the pieces of newspaper, plaster of Paris cream, also all over the foot to above the ankle joint so as to fill the upper part of the pan and extend, in the form of a pyramidal surface, up to a point above the ankle joint, as shown in Fig. 8. Now, I provide a rectangular piece of burlap 21 and lay it over the top of the said plaster of Paris, while the plaster is still mobile and has not yet set, by carrying the two ends of the burlap 21 to the front around the ankle from the rear of the plaster and lapping over at the front thereof, as shown in Figs. 8 and 9. Thereupon, while the plaster is still in the formable condition, before it has set, I pat down on the top of the burlap, with the hands, all over the wet plaster. This supplies pressure which is substantially equalized all over the exterior of the foot. However, the degree of the pressure may be controlled and applied to a varying extent, according to the amount of pressure desired to be applied to the exterior of the foot. This results in applying a tightness to the foot tissues in the case of soft feet, and the degree of tightness applied may be checked according to the tightness felt by the person on whose foot the cast is being made. This can be modulated according to the softness of the particular foot and according to the purpose to be attained. For instance, in the case of sportswear, and especially in the case of skating shoes or dancing shoes which are to be made on the plaster positive cast made from said negative, the tightness of the negative cast on the foot will be increased to provide the type of footwear desired in the case of the different athletes, as in dancing or skating. This tightness will compress the tissues of the foot and even force the blood, to some extent, up into the leg due to the compression applied, all of which is accomplished while the relative shape of the foot, and particularly the toes and adjacent metatarsal part of the foot, is retained.

Just before the plaster of Paris becomes rock-like in hardness, which is approximately five or six minutes from the time the plaster is applied to the foot, the burlap 21 is stripped off and, owing to the two vertical scorings or indentations made at the opposite sides of the cast, the upper negative cast is made ready to be split into two pieces, a front upper portion 22 and a rear upper portion 22a. After an additional five minutes the mass of plaster becomes very hard and the foot is then lifted up, together with the plaster and the pan, having the front piece 22 and the rear piece 22a and an underneath cast 23 of the plaster supported by the foot. The pan is then tapped lightly on the edge, which results in the pan, carrying the bottom piece 23 of the negative cast, falling away from the foot. With a screw driver, the forward and rear pieces 22 and 22a of the cast can now be separated at the vertical scorings on the sides thereof.

In order to make the positive cast therefrom, the toe-lock 2 is taken off the foot and stuck into its proper place in its recess in the inside of the forward piece 22 of the negative cast. The negative cast is now fastened together with rubber bands or "Duco" cement. This negative cast is then flushed out with a water solution of silicate of soda to provide a separation surface, from the plaster of the positive cast to be made therein. Thereupon, the plaster of Paris cream is poured into the negative cast while vibrating the latter slightly and the plaster is then allowed to harden. A positive cast is thus obtained having all the actual details of the foot, including the correctly maintained position of the toes, which has been unaltered by any involuntary inclination of the foot to produce a movement of the toes during the casting operation.

With this truly accurate positive cast any type of foot-wear, in accordance with any of my previous processes or ways of producing shoes, sandals, etc., may be made, for example the thin type of sandals shown in my Patent No. 2,404,483, granted July 16, 1946.

Also, instead, if desired I may make a toe-lock, such as the toe-lock 1 or the toe-lock 2, on this completely accurate positive cast, by the methods described hereinabove.

Furthermore, if desired, having made this cast toe-lock, I can apply the toe-lock to this cast and then make a shoe by any of the molding methods as set forth in my previous patents or applications for Letters Patent. In such a shoe, the toe-lock 1 or 2 could be worn next to the foot with the stocking outside the toe-lock, and in this way any displacement of the toes, due to sock tension, could be entirely eliminated. In this way, maintenance of the foot in its correct position is insured in the shoe even more effectively than if the shoe were molded on the foot without the aid of the toe-lock or toe-positioner. In other words, the toe-lock becomes the third member, in addition to the sock and shoe, which fills up the unoccupied space in the shoe at such places as might not have been made to conform completely to the foot when the shoe is molded on the foot without the aid of the toe-lock. This will be apparent from the fact that if a complete shoe were molded with all the toe-lock contours molded into the shoe, the shoe could neither be placed on the foot nor withdrawn from the foot. In other words, the physiological accuracy of the toe-lock compared to the shape of the toes and the metatarsal portion of the foot is substantially the same as if the person were walking in a terrain of sand or soft mud, which induced the formation of the interdigital contours in the course of natural evolution.

Furthermore, a composite insert 24 can now be made on the foot, or on any cast made as above with the toe-lock 1 or 2, following the process in my patent referred to above, No. 2,177,304, or with the modified casting procedure involving the said toe-lock 1 or 2 in which the mound of plaster, shown in Figs. 8 and 9, is subjected

to pressure to tighten up the tissues of the foot, which composite insert may embody said toe-lock 1 or 2 as well as a pyramid 25. The pyramid 25 may be carried by a lower flap or member 26 which is located opposite to the interdigital extrusions 6 between the respective toes, carried on an upper flap or member 27 of the toe-lock, as described above. In order to make the composite insert 24 I may utilize the toe-lock 1 or 2, but, preferably, I may utilize the toe-lock produced hereinabove before being trimmed off around the marginal edges thereof. Accordingly, the untrimmed toe-lock 1 or 2 is placed on the foot or on the cast produced by the procedure of said Patent No. 2,177,304, or by the cast produced by the plaster compression technique described hereinabove. Also, before placing the said toe-lock on the foot or cast it is preferably provided with a thin coating of Vaseline on the lowermost ends of the several different interdigital extrusions 6, which extend downwardly between the respective toes. Then, the underneath forward part of the foot is coated with a thickened latex. Thereupon, I provide a piece of jersey cloth 28 such as referred to above, powdered with plaster of Paris, and, placing it underneath the forward part of the foot, I press it up with the fingers, into the contours of the forward portion of the foot and especially so as to form the pyramid in the recesses between the toes respectively, and between the toes as a group and the metatarsal portion of the foot. I then coat the jersey cloth 28 all over the underside with the latex. Beneath the said jersey cloth 28 and in the cavities therein formed as above, I now fill in the cavities therein formed as above with the felted latex mud made as hereinabove described. However, the cubic granulas of felt may be substituted by crumbs of foam-rubber, which are in the form of pellets or granules, about the size of Grapenut grains, a product which is known on the market under the name of "foam rubber crumbs," and which is a foam-rubber, either of natural or synthetic rubber, having very small or microscopic pockets therein. Then, I pinch together the outer margins of the toe-lock and the jersey cloth 28 all around the front margins thereof so as to make substantially a horizontally extending web of the top and bottom fabrics, which are then trimmed off with scissors around the foot margin. Another cover piece of jersey cloth 29 powdered with plaster of Paris, of the same type but which may be somewhat smaller than the piece of cloth 28, is then placed over the top of the toe-lock 1 or 2 and below the piece 28, which has had applied to the inner surface of the cloth 29 thickened latex, which may be also trimmed off around the foot margin. Instead of the cover piece 29, however, I preferably use for this purpose the toe-portion of a sock 30, powdered with plaster of Paris, which is now placed over the top 27 and bottom 26 of the insert after the latter has been coated on top and bottom with thickened latex. Preferably, also, the said cloth 29 and 30, after being applied to the foot, may be coated with thickened latex and thereafter dusted with powdered plaster of Paris. In either case, whether made with the cover 29 or the sock 30, the composite insert 24 is, when partially set, trimmed by cutting off the same on a vertical line 31 extending through the middle of the big toe and on a vertical line 32 extending through the middle of the little toe, thus leaving the extreme outside of the foot, including the lateral portions of said big toe and little toe, uncovered. Also, if desired, the rear toe-lock margin 27 and the underneath rear margin 26 may be trimmed off into curved lines, as shown in Fig. 14.

As an alternative, in making the said insert 24, instead of making the toe-lock 1 or 2 therein with neoprene latex mud I may substitute for the latter a molding clay known as "Plastelene," hereinabove referred to, so that then the completed composite insert 24 would have within the same the interdigital extruded toe-separators 6 made with the Plastelene. This remains mold-

able and plastic as it is a non-setting material, and would act substantially the same as a body of ordinary mud in a natural terrain, in which the foot might be walking. Also, as shown in Fig. 14, I may provide a plurality of series of ventilating perforations 33 corresponding to the lines above and below the respective toes, in both the under portion 27 and the lower portion 26 thereof.

Now, I can make a shoe having substantially no top and bottom detail, at the portion of the foot comprising the toes and the adjoining metatarsal part of the foot, by placing this composite toe positioner, which includes the interdigital toe-separating elements 6 and pyramid 25, on the foot or on an accurate cast of the foot made by any one of the applicant's processes for making a cast of the foot, and the shoe may be made thereon by any one of the applicant's molding methods, as set forth in any of the applicant's issued patents or applications for Letters Patent relating thereto. In other words, with said composite inserts 24 and shoes made in this way, when worn on the foot in the shoe and with or without a sock covering the foot and insert, the insert fills in the free space between the shoe and the foot. Also, because of this fact, the inserts 24 enable stock shoes of the ordinary kind to be worn on the feet with a great degree of comfort and effectiveness because the insert occupies the front part of the shoe to support the foot against the non-fitting contours of such shoes when not molded to fit the feet.

Still another alternative procedure may be followed, by making a negative plaster of Paris cast utilizing any of the procedures above referred to, with the toe-lock 1 or 2 on the foot or the insert 24 on the foot. When the negative cast has been made the toe-lock 1 or 2 or the insert 24 can be removed from the foot. After this has been done, the plaster of Paris cream may be poured into the negative cast while not containing the toe-lock 1 or 2 or the insert 24 therein. This results in the making of a positive cast which does not have thereon the top and bottom detail contours of the toes and adjacent metatarsal portion of the foot. By using this positive cast so made I may build thereon a shoe by any of the molding methods described in any of my preceding patents and applications for Letters Patent relating to the molding or building of shoes. Molded shoes made in this way can then be worn on the feet having thereon the toe-lock 1 or 2 or insert 24 and with or without a sock over the same. Or it is feasible to wear such a toe-lock or insert on the foot with or without a sock over the same and within a simple pair of ordinary athletic shoes or even rubbers, without danger of the forward part of the foot becoming deformed by the non-fitting shoe contours, because the said contours do not actually contact with the feet. This positioning of the toes and forward part of the foot is doubly effective when the interdigital elements 6 and the pyramid 25, as a result of the molding operation, actually meet, although it is not essential that they always meet. Also, the construction of the toe-lock and insert gives such complete control over the falangal portion of the foot as to provide means for producing orthopedic corrections in a most effective way, which is comparable to orthodontistry.

It will be understood that the insert 24, being of very flexible material, can be turned inside out so as to permit the inner surface to be brushed out, but also so as to remove the superficial rubber in order to expose the fibers of the fabric, if desired. Similarly, if desired, the inner surface can be provided with a further coating of latex, but if a latex or rubber surface is retained inside the composite insert 24, it is preferable in wearing to provide the same with a coating of powdered talc, or talcum powder, to prevent the surface from being adherent.

Still another way of obtaining a modified cast for use in shoe making is by putting the toe-lock 1 or 2 or com-

posite insert 24 on the foot. Then an athletic heavy weight sock of cotton or wool 41 is pulled over the foot. Meantime, a basin of very soft plaster of Paris and water, having the consistency of milk, is prepared and with the hand this plaster of Paris milk is rubbed all over the sock repeatedly while at times slightly resting the foot on the ball surface, such as the surface 14. In order to position the foot, for applying a heel if desired, the rear of the foot, when on a support, such as the surface 14, during this operation, may be supported upon a small lump of "Plastelene" 42. Thereupon, I provide a number of pieces, generally about twenty-four, each having a width of 2", of "plaster of Paris bandages" 43, which may be cheesecloth having unset plaster of Paris distributed throughout the meshes of the cloth. These plaster of Paris bandages are wound around all over the sock 41, after each bandage has been dipped in water. The winding of these bandages on the foot may be accomplished with or without tension but for making certain types of shoes, as for skating, dancing or athletics, or even style production, the bandages 43 can be tightly wound around the foot, but care should be taken not to wind the bandages so tight as to injure the foot. Also, for skating and dancing shoes, the plaster of Paris bandages are preferably wrapped considerably higher around the calf of the leg. When the plaster of Paris in the bandages 43 has set, which is in about fifteen to twenty minutes after being dipped in water and applied to the foot, I may make a slit 44 down the front of the foot through said bandages with surgical scissors, after which the negative thus produced, by the plaster of Paris which has partly set preferably, is removed from the foot and then one long strip of wet but unset plaster of Paris bandage is wrapped around the shoe. This composite plaster of Paris bandage now forms a negative in which a positive plaster of Paris cast may be made after first applying to the interior thereof a water solution of silicate of sodium to provide a good separation from the positive. Thereupon, I pour into the negative a plaster of Paris and water mixture having a consistency of cream, to make the positive cast.

While I have described my invention above in detail I wish it to be understood that many changes may be made therein without departing from the spirit of the same.

I claim:

1. A cast conforming to foot-form contours embodying in the cast the conformation of toes separated by an interdigital toe separator having on said separator an underneath toe recess pyramid.

2. A negative cast conforming to the contours of a foot-form embodying in the front portion thereof a hollow toe section of slightly greater volume than that occupied by the toes, said volume being just large enough to receive the toes with an interdigital toe separator positioned thereon which separator includes a sheet of material that covers a plurality of said toes.

3. A negative cast conforming to foot-form contours embodying in the cast the conformation of toes separated by an interdigital toe separator having on said separator an underneath toe recess pyramid.

4. A positive cast conforming to foot-form contours embodying in the cast the conformation of toes separated by an interdigital toe separator having on said separator an underneath toe recess pyramid.

5. The process which comprises making a cast by applying a toe-positioner to a foot so as to separate toes thereon, applying pressure to the under surface of the foot to give the foot a desired position, applying to the opposite side of the foot a material adapted to set while conforming to the contours of said opposite portion of the foot as determined by said toe-positioner, allowing the material to harden, removing the pressure from the first mentioned portion of the foot and pressing said first men-

tioned portion of the foot in a soft viscous material adapted to set, while said hardened mass of material remains on said opposite side of the foot.

6. The process which comprises making a cast by applying a toe-positioner to a foot so as to separate toes thereon, applying pressure to the under surface of the foot by a foot-supporter to give the foot a desired position, applying to the opposite side of the foot a material adapted to set while conforming to the contours of said opposite portion of the foot as determined by said toe-positioner, allowing the material to harden, removing the pressure from the first mentioned portion of the foot and pressing said first mentioned portion of the foot in a soft viscous material adapted to set, while said hardened mass of material remains on said opposite side of the foot.

7. In the manufacture of a negative cast having a hollow toe section therein of volume slightly greater than that of the toes, which hollow toe section is made just large enough to receive the toes with an interdigital toe separator positioned thereon, which separator includes a sheet of material that covers a plurality of said toes, the method which comprises the steps of separating the toes on a foot-form and covering a plurality of toes with a sheet of material by placing the toe separator on such foot-form, applying a molding material to said foot-form which material is adapted to set and form a cast thereof, and maintaining the toe separator in place on the foot-form while such molding material hardens to prevent the molding material from penetrating into the spaces between adjacent toes.

8. The method described in claim 7 which includes the step of molding a positive cast in the negative cast with said toe separator in place therein.

9. The method described in claim 7 which includes the steps of applying a plaster of Paris slurry to the said foot-form as the molding material and then allowing the plaster to harden to form a negative cast thereon.

10. The process described in claim 7 which includes the steps of applying plaster of Paris bandages to said foot-form as the molding material and then allowing the plaster bandages to harden to form the cast.

11. In the manufacture of a negative cast having a hollow toe section therein of volume slightly greater than that of the toes, which hollow toe section is made just large enough to receive the toes with an interdigital toe separator positioned thereon, which separator includes a sheet of material that covers a plurality of said toes, the method which comprises the steps of separating the toes on a foot and covering a plurality of the toes with a sheet of material by placing the toe separator on the foot, applying a material to said foot which material is adapted to set and form a cast thereof, and maintaining the toe separator in place on the foot while such molding material hardens to prevent the molding material from penetrating into the spaces between adjacent toes.

12. The process which comprises placing the lower portion of the foot having a toe-positioner separating toes thereon in a molding material, putting a layer of separating material on the molding material and applying a moldable material to the top of the foot to form an upper negative while supported in said molding material.

13. The process which comprises placing the lower portion of the foot having a toe-positioner separating toes thereon in a molding material, putting a layer of separating material on the molding material, applying a moldable material to the top of the foot to form an upper negative while supported in said molding material, then separating the upper and lower negatives and separating the upper negative into sections, joining the negative portions together and making a positive therein.

14. The process which comprises suspending the lower portion of the foot having a toe positioner separating toes thereon in a molding material, putting a layer of separating material on the molding material and applying

a moldable material to the top of the foot to form an upper negative while pressing on said molding material.

15. The process which comprises suspending the lower portion of the foot having a toe-positioner separating toes thereon in a molding material, putting a layer of separating material on the molding material, applying a moldable material to the top of the foot to form an upper negative while pressing on said molding material, then separating the upper and lower negatives and separating the upper negative into sections, joining the negative portions together and making a positive therin.

16. The method of making a cast which includes the steps of separating the toes of a foot by applying a toe positioner thereon, pressing the bottom of the foot against a spherical surface to give the bottom of the foot curvature which simulates the natural curvature of the foot when held in space, applying a material to the upper portion of the foot which material is adapted to set while conforming to the contours of said upper portion of the foot as determined by said toe positioner, allowing the material to set and then pressing the lower portion of the foot into a mass of material adapted to set and form a cast while said material remains in place on the upper portion of the foot.

17. The method described in claim 16 which includes the steps of applying a felt covering to the spherical surface and then applying a sand covering over said felt which felt and sand layers conform to the spherical surface of the support.

18. The method which comprises the steps of separating the toes of the foot by applying a toe positioner thereon, placing the lower portion of the foot in a mass of material adapted to set while it conforms to the contours of the foot with the toe positioner in place thereon, allowing the material to set to form a self-sustaining cast, thereafter applying a material to the upper portion of said foot which material is adapted to set and form a cast and then allowing such material to set on the upper portion of the foot to form a negative cast thereof.
